Patented Apr. 27, 1915.

UNITED STATES PATENT OFFICE.

VINZENZ ZSUZSITS, OF AURORA, ILLINOIS, ASSIGNOR OF ONE-FOURTH TO C. H. FRANZ,
OF AURORA, ILLINOIS.

DOOR-LATCH.

1,137,107.

Specification of Letters Patent. Patented Apr. 27, 1915.

Application filed July 20, 1914. Serial No. 852,025.

To all whom it may concern:

Be it known that I, VINZENZ ZSUZSITS, a subject of the King of Hungary, residing at Aurora, in the county of Kane and State 5 of Illinois, have invented certain new and useful Improvements in Door-Latches; and I do declare the following to be a full, clear, and exact description of the invention, such as will enable others skilled in the art to 10 which it appertains to make and use the same.

My invention relates to improvements in locks and latches and more particularly to the latter.

15 The primary object of the invention is to provide a device of the hereinafter described character which may be easily and cheaply manufactured and which will readily perform the functions for which it is 20 designed.

In carrying out the above end, a secondary object becomes to provide simple and efficient means for supporting a gravity catch member in the outer edge of a door.

25 With the above objects in view, the invention resides in certain novel features of construction and combination herein described and claimed and shown in the drawings wherein:—

30 Figure 1 is a front elevation of a screen door and its frame, showing the application of my invention thereto; Fig. 2 is an enlarged front elevation of a portion of the frame and the adjacent portion of the door and illustrating more clearly the parts shown in Fig. 1; Figs. 3 and 4 are respectively vertical and horizontal sections taken on the lines 3—3 and 4—4 of Fig. 2; Fig. 5 is an inside elevation of the parts seen in Fig. 2; Fig. 6 is a perspective view of the gravity catch; and Fig. 7 is a similar view of the pivoted pawl employed for locking the same against movement.

45 In the accompanying drawings, I have illustrated a screen door D which is hinged at H within the usual frame F, a suitable spring (not shown) being preferably employed for normally closing said door. The free upright edge of the door D is recessed a transversely as indicated at 1 to receive a rectangular attaching plate 2 whose parallel upright edges are provided with outwardly extending flanges 3 and 4 which terminate 50 flush with said free edge of the door D. The flange 3 is provided with an inverted

L-shaped slot 5 whose horizontal portion opens through its free edge while the flange 4 is notched as indicated at 6, these provisions being made for a purpose to become evident. The plate 2 may be secured to the door D in any suitable manner but preferably by a pair of screws 7 (see Fig. 3).

Pivoted to the side portion of the plate 2, adjacent the flange 3, by a suitable pivot stud 8, is a gravity latch 9 which is here shown as formed of an elongated strip 10 of sheet metal having one end offset as indicated at 11 and then extended longitudinally as seen at 12, said portion 12 having an opening 13 which receives the pivot stud 8. By this formation, the portion 12 of the plate 10 is offset longitudinally on the opposite portion 14 thereof, said portion 14 being notched on its under side as clearly seen at 15 for coaction with a screw or other suitable stop 16 which projects inwardly from the adjacent portions of the frame F. As clearly seen in Figs. 3 and 6, the outer end of the portion 12 inclines upwardly and outwardly as indicated at 12' while the other end of the portion 14 inclines outwardly and upwardly as indicated at 14'. It will further be seen that the portions 12 and 14 are provided with laterally projecting operating ears 17 and 18 respectively which are formed integrally with their upper edges. The extreme outer end of the portion 14 is preferably bent slightly to one side as indicated at 19 in order to prevent said end from striking the door frame when the door is closed or opened, for which purpose said frame is preferably recessed as indicated at 20 in the drawings.

When the parts are assembled, the end portion 12 of the plate 10 contacts with the attaching plate 2 while the opposite end portion 14 thereof is spaced a considerable distance from said plate as clearly seen in Fig. 4, thereby allowing its inclined outer edge 14' to contact with the screw 16 as the door closes, thus raising the weighted end of the latch 9 which again falls when the notch 15 is located above said screw, thus effectually latching the door in closed position.

105 In most cases, it becomes expedient to provide means whereby the latch 9 may be positively locked against movement and for this purpose, I have provided a pawl or button 21 which is pivoted at 22 to the up- 110

per end of the flange 4, the lower outer edge of said pawl being notched as at 23 for engagement with the upper edge of the catch 9 and being provided with an operating ear 24 by means of which it may be readily swung around its pivot to assume the position shown in full lines in Fig. 5 in which position it is inoperative or to assume that shown in dotted lines in said figure for the purpose of preventing the weighted end of the catch 9 from being raised.

From the foregoing description, taken in connection with the accompanying drawings, it will be seen that I have produced an extremely simple door latch which may be inexpensively manufactured yet one which will be highly efficient in operation.

Having thus described my invention, what I claim as new and desire to secure by Letters Patent is:

In a device of the character described, an upright vertically elongated attaching plate designed to be secured within a notch in the free edge of a door, said attaching plate having laterally projecting flanges on its

upright side edges, one of said flanges having an upright notch in its free edge, and the other flange having an upright slot, a horizontally elongated latch plate pivoted to said attaching plate to swing in a vertical plane, one end of said latch plate being extended outwardly through the upright slot and contacting with the upper end thereof, and the other end of said latch plate being offset from the attaching plate and extending outwardly through said notch, said last named end having a locking notch in its lower edge, and being inclined upwardly and outwardly from said notch, and operating ears spaced outwardly from the flanges of the attaching plate and formed integrally with the ends of the latch plate.

In testimony whereof I have hereunto set my hand in presence of two subscribing witnesses.

VINZENZ ZSUZSITS.

Witnesses:
